CLAIM

The ornamental design for a position monitoring appliance, as shown and described.

DESCRIPTION

FIG. 1 is a front perspective view of a position monitoring appliance, showing my new design.

FIG. 2 is a front elevation view thereof.

FIG. 3 is a rear elevation view thereof.

FIG. 4 is a right elevation view thereof.

FIG. 5 is a left elevation view thereof.

FIG. 6 is a top elevation view thereof.

FIG. 7 is a bottom elevation view thereof; and,

FIG. 8 is a rear perspective view of the position monitoring appliance showing an attached antenna.

(Continued)

The broken lines in the drawings illustrate portions of position monitoring appliance which form no part of the claimed design.
